By his Attorney E. W. Scherr Jr.

UNITED STATES PATENT OFFICE.

ROBERT HEAD, OF YONKERS, NEW YORK, ASSIGNOR TO THE AEOLIAN COMPANY, A CORPORATION OF CONNECTICUT.

EXPRESSION DEVICE FOR PHONOGRAHS.

Application filed September 4, 1920. Serial No. 408,225.

To all whom it may concern:

Be it known that I, ROBERT HEAD, a citizen of the United States of America, residing at Yonkers, Westchester County, New York, have invented certain new and useful Improvements in Expression Devices for Phonographs, of which the following is a specification.

My present invention relates to means for automatically repeatedly operating the tone-volume control of a phonograph. This varies the volume of the tone as long as the device is in operation, and produces an effect which I have discovered relieves the monotony of the average phonograph rendition and actually increases the pleasurable effect. The device can be thrown out of operation at will, and then does not interfere with the operation of the volume control device by hand.

The drawings illustrate the preferred form of my invention, and is only one of the specific embodiments my invention is adapted to take. In them, Fig. 1 is a fore and aft vertical section, partly in elevation, of a phonograph equipped with my present invention; Fig. 2 is a plan view on an enlarged scale as compared with Fig. 1 of a part of the motor-board showing the parts of my device that are supported thereby; Fig. 3 is a side-elevation of the parts in Fig. 2 as looked at from the lower side of said Fig. 2; Fig. 4 is an underneath plan view of the parts in Fig. 2; and Fig. 5 is the same as Fig. 4 except that the parts of my present device are shown adjusted into their non-operating position so as not to operate the tone-volume control device.

Describing now the specific embodiment of my invention illustrated in the drawings,—1 is the cabinet of the phonograph containing the usual sound-box, tone-arm and horn 2. 3 is the usual removable motor-board, so called because it supports the spring- or other motor that drives the spindle 5 and turn-table 6.

7 represents any tone-control device, in this case comprising a soft rubber throat within the neck of the horn, with which a soft rubber plug-valve on a vertical valve-stem 8 co-operates.

Manual means for reciprocating this valve and valve-stem comprises the following,—9 is a link connecting the lower end of the valve-stem with one arm of an elbow-lever 10 pivotally supported at 11, the other arm

of said lever being constantly pulled on by a spiral spring 12 attached to the bracket 13. This spring tends constantly to retract the plug-valve away from the throat.

To operate the valve in the opposite direction, a lever 14 is provided, pivotally supported at 11 and adapted to be pulled against a pin 15 projecting from the side of the elbow-lever by a wire 16 connected to the knob 17. Loosely surrounding the wire is a casing 18, one of whose ends is secured stationarily to a bracket 19 and its other end is attached to the handle 20.

By pulling the knob 17 away from the handle 20, the plug valve is moved towards the throat, whereas pushing the knob towards the handle permits the spring to retract the valve to open the throat to play louder.

Describing now my means for automatically operating the valve:—21 is a rod whose lower end is pivotally connected to the valve-stem 8 and whose upper end is pivotally connected to one arm of an elbow-lever 22 pivotally supported at 23.

24 is a gear driven by the upper or driving gear of the spring-motor 4, said gear being secured to a vertical spindle 25 (turning in the bearing 27) having a crank-arm 28 on its lower end. 29 is a connecting-rod operatively connecting said crank-arm with a reciprocating tubular member 30 slidably mounted on the arm 31 of a rock-shaft 32 supported in the bearing 33 said rock-shaft at its upper end having another arm 34 connected by a link 35 with a pin 36 on the enlarged head 37 constituting the lower end of the rotatable stud 38 supported in a vertical hole through the motor-board 3.

The upper end of said rotatable stud 38 is provided with a knurled operating-head 39 and a pointer 40, the latter playing over a stationary dial 41 marked "on" and "off" (Fig. 2).

42 is a pin on the underside of the motor-board coacting with the shoulders 43—43 on the aforesaid lower head 37 of the stud 38. These limit the rotation of the stud when turned by its knurled head 39 to the distance between the two positions "on" and "off" (Fig. 2) shown on the dial. When the pointer 40 is at the "on" position, as in Fig. 2, then the link 35 will have rotated the rock-shaft 32 into the position shown in Figs. 1, 2, 3 or 4, thereby positioning the

arm 31 so that the end of the reciprocating tubular member 30 is in operative alignment with the arm of the elbow-lever 22.

The result is that as said member 30 is 5 slowly reciprocated back and forth on said arm 31 (by the above described connecting rod 29 and crank-arm 28 driven by the spring-motor through the gear 24 and shaft 25), the bell-crank 22 is repeatedly swung 10 first to the left and then to the right, each left-hand swing (Fig. 1) gradually closing the tone-control valve to reduce the volume of the tone, and each right-hand swing doing the reverse.

15 It may be noted that the right-hand swing of the elbow-lever is produced by the spring 12 (Fig. 1) as and when permitted by the right-hand reciprocation of the reciprocating member 30. 45 (Fig. 1) is a fixed stop 20 which engages the elbow-lever 22 when the latter is in the position shown in Fig. 1, thereby making this the limit of the right-hand swinging of said lever.

To throw out of operation the described 25 automatic operation of the tone-volume control, the operator merely rotates the knob 39 to carry the pointer 40 (Fig. 1) to "off" 30 to carry the pointer 40 (Fig. 1) to "off" on the dial. This acts to position the parts in the positions shown in Fig. 5, wherein 35 the reciprocating member 30 is out of alignment with the elbow-lever 22 and therefore cannot operate it or the tone-control device, in spite of the fact that said member 30 keeps on reciprocating because constantly 40 driven by the spring-motor that operates the phonograph.

The relative size of the operating gears of course determines the time or duration of the alternating reductions and increases in 45 tone-volume when the automatic device is in operation. This should be fairly slow and gradual to produce an artistic effect in accord with good taste.

Next the means for connecting the link 45 35 and the pin 36 deserves special mention. This is best shown by comparing Figs. 2, 3, 4 and 5; and consists of a hole 46 (Figs. 2 or 4) in the link freely receiving the headed pin 36, with a piece of tensioned spring-wire 50 47 having its ends secured to the pin and link and yieldingly tending in the plane of Fig. 2 or 4 to force said link and pin away from each other.

This yielding resilient connection comes 55 especially into use as follows: Suppose the phonograph is in operation, and the operator turns the knob 39 (Fig. 2) to put on the automatic control as shown in said figure. The chances are that in doing so, the constantly reciprocating member 30 will be in 60 its extended position and will strike against the side 22^a of the elbow-lever 22. This will prevent said member 30 from coming into its operative position shown in Fig. 2 65 but, due to the play allowed between the en-

larged hole 46 in the link 35 and the pin 36, will not prevent the operator from bringing the pointer 40 and said pin 36 into the "on" position shown in Fig. 2 or 4.

The result will be that the spring 47 will 70 be additionally compressed and will automatically snap the link 35, the crank-arms 34—31, and the reciprocating member 30 into their operating position shown in Fig. 2 as soon as, towards the end of the next 75 right-hand reciprocation of said member, it clears the elbow-lever 22.

On the other hand, the spring 47 cannot react on the pin 36 and the head 37 to rotate the pointer member 40 back towards 80 the "off" position, because of the mechanical disadvantage due to the arrangement of the centers comprising the center of the hub 27, the pin 36 and the point of attachment of the spring 47 with the link 35.

It will be noted that when the automatic means is out of operation, the tone-control can be operated manually from the handle 20 and knob 17 to suit the individual taste of 85 the operator.

Of course, only a portion or portions of the above embodiment can be used; also equivalents may be substituted for the parts shown or modifications can be made which will be apparent to those skilled in the art 90 from an understanding of my invention, but which still will be within the spirit and scope of my invention and of the annexed claims.

What I claim is:

1. In combination with a phonograph, a tone-volume control, and automatic means which operates said tone-volume control to produce repeatedly tone-volume variations. 100
2. In combination with a phonograph, a tone-volume control, and motor-driven means which repeatedly operates said tone-volume control. 105
3. In combination with a phonograph, a tone-volume control, motor-driven means 110 which repeatedly operates said tone-volume control, and means for throwing said motor-driven means into and out of action.
4. In combination with a phonograph, a tone-volume control, means for manually 115 operating same, motor-driven means which repeatedly operates said tone-volume control, and means for throwing said motor-driven means into and out of action.
5. In combination with a phonograph, a 120 tone-volume control; means constantly tending to operate said control in one direction; manual means for operating said control in the reverse direction by contact therewith, so that the control means can be operated 125 independently of said manual means; motor-driven means which repeatedly operates said tone-volume control; and means for throwing said motor-driven means into and out of action. 130

6. In combination with a phonograph, a tone-volume control; means constantly tending to operate said control in one direction; an operatively supported and connected lever for operating said control in the opposite direction; and a motor-driven reciprocating member adapted to contact with and operate said lever. 40
7. In combination with a phonograph, a tone-volume control; means constantly tending to operate said control in one direction; an operatively supported and connected lever for operating said control in the opposite direction; a motor-driven reciprocating member adapted to contact with and operate said lever; and manual means adapted to shift said motor-driven reciprocating member and said lever into and out of operative contact. 45
- 10 8. In combination with a phonograph, a tone-volume control; means constantly tending to operate said control in one direction; an operatively supported and connected lever for operating said control in the opposite direction; a motor-driven crank, link-connected to a reciprocating member mounted on a support; and means including a yielding resilient connection adapted to move said support and reciprocating member into operative relationship with said lever, said means being reversely operative to take the parts out of operative relationship. 50
- 15 9. In combination with a phonograph, a tone-volume control; means constantly tending to operate said control in one direction; a motor-driven reciprocating member adapted to contact to operate said control in the opposite direction; manually operable means also adapted by contact to operate the control in said opposite direction; and means for shifting the reciprocating mem- 55
- 20 10. In combination with a phonograph, a tone-volume control; means constantly tending to operate said control in one direction; an operatively supported and connected lever for operating said control in the opposite direction; a motor-driven crank, link-connected to a reciprocating member mounted on a support; and means including a yielding resilient connection adapted to move said support and reciprocating member into operative relationship with said lever, said means being reversely operative to take the parts out of operative relationship. 60
- 25 11. In a phonograph, the combination with a rotatable record support, a motor for actuating the support, and a sound conduit, of a tone regulator coacting with the sound conduit, and connections between the tone regulator and the motor whereby the tone regulator is actuated by the motor, substantially as and for the purpose described. 65
- 30 12. In a phonograph, the combination with a rotatable record support, a motor for actuating the support, and a sound conduit, of a tone regulator coacting with the sound conduit, connections between the tone regulator and the motor whereby the tone regulator is actuated by the motor, and means for connecting and disconnecting the tone regulator to the motor, substantially as and for the purpose specified. 70

In testimony whereof, I have signed my name to this specification, this third day of September, 1920.

ROBERT HEAD.
